RACK FOR DISPLAYING AND MERCHANDISING CONFECTIONERIES OR THE LIKE

Joseph Kiegel, Glen Cove, and Robert B. Kyle, Manhasset, N.Y., assignors to American Chicle Company, Long Island, N.Y., a corporation of New Jersey

Filed June 24, 1958, Ser. No. 51,502

Term of patent 7 years

(Cl. D80—10)

FIG. 2FIG. 3Fig. 1 is a front perspective view taken from the left side of a rack for displaying and merchandising confectioneries or the like embodying my new design;

Fig. 2 is an enlarged transverse sectional view thereof showing the third shelf from the top; and

Fig. 3 is an enlarged transverse sectional view thereof showing the bottom two shelves.

We claim:

The ornamental design for a rack for displaying and merchandising confectioneries or the like, as shown and described.
